UNITED STATES PATENT OFFICE.

ALEXANDER LECLAIR, OF MONTREAL, CANADA.

GAINING-MACHINE.

No. 821,654.

Specification of Letters Patent.

Patented May 29, 1906.

Application filed February 16, 1906. Serial No. 301,430.

To all whom it may concern:

Be it known that I, ALEXANDER LECLAIR, a subject of the King of Great Britain, residing at 195 Delinel street, in the city and district of Montreal, in the Province of Quebec, in the Dominion of Canada, have invented certain new and useful Improvements in Gaining-Machines, of which the following is a specification.

10 This invention relates to improvements in gaining-machines, as described in the present specification and illustrated by the accompanying drawings, that form part of the same. The invention consists, essentially, of a 15 plurality of standards, shafts journaled there-in, adjustable pedestals arranged in proxim- ity thereto, rotating knives mounted on said shafts and pedestals, a carriage traveling over said standards, clamping mechanism attached 20 to said carriage, and a replaceable table resting in said carriage.

The objects of the invention are to simul- 25 taneously make a number of cuts in such ar- ticles as belt-rails used in car construction and without changing the position of said belt-rail in the carriage or said machine to finish the number of cuts necessary, and thus complete the full number required and turn 30 out said belt-rail ready for use and to provide in such a machine a facility in operation and absolutely secure means of retaining said belt-rail in position during the operation of cutting.

In the drawings, Figure 1 is a general per- 35 spective view of the machine. Fig. 2 is a plan view of a portion of the machine from above. Fig. 3 is an elevation of the machine from one end. Fig. 4 is a side elevation showing a detail of the clamping mechanism. Fig. 40 5 is an end view of the clamping mechanism shown in Fig. 4. Fig. 6 is a detail of the running-gear, showing the locking mechanism. Fig. 7 is a cross-sectional view of the running- 45 gear through A B in Fig. 6. Fig. 8 is a verti- cal section of a pedestal. Fig. 9 is a perspective detail of a knife. Fig. 10 is a perspective detail of a knife-blade.

Like characters of reference indicate corresponding parts in each figure.

50 Referring to the drawings, *a* represents the standards having the upward extensions *b* at the rear thereof. *c* is a tie-rod extending through the upper ends of said rear portions *b* of the standards and secured on the upper 55 side of each end portion by the set-screws *d*.

e is a tie-rod extending through the stand- ards at *f* and securely bolted on the outer side of each end standard, and *g* represents tubes encircling said rod *e* between said stand- ards and spacing the same one from the other. 60

h is a shaft journaled in the bearings *i* in the standards and having at one end thereof the pulley *j*, which is suitably connected with the driving mechanism by the belt *k*.

l is a knife having an elongated body por- 65 tion *m* and mounted on the shaft *h* and rotat- ing therewith. *n* is a set-screw inserted in a correspondingly-threaded orifice in said body portion *m* and having its inner end abutting the said shaft *h*.

o represents knife-blades secured on the flattened ends *p* of the body portion *m* by the bolts *q*. The blades *o* have a chisel edge *r* and flanges *s* extending up each side at right angles to the flat of the blade *o*, said 75 flanges at their outer ends having the chisel edges *t*, terminating in the projecting sharp points *u*, so that the said edges *t* of the flanges are the first portion of the knife to engage the material to be cut, thus starting an incision 80 in the material on each side of the cut to be made, which is readily followed up by the edge *r*. The inwardly-projecting flanges, which are upwardly projecting in the opera- 85 tion of cutting, form the means of making a perfectly clean cut from the edges.

v represents hoods supported on the tubes *g*, which pass therethrough, and further sup- ported by the arm *w*, secured on the rod *c*, which passes through the upward extensions 90 *b* at *y* and to the top of the said hoods. The hoods *v* each shield one of the knives *l*.

z is a bed-plate extending along the full length of the machine at the front thereof and firmly secured to the flooring by the bolts 2. 95

3 is a guideway formed longitudinally at each side on top of the plate.

4 represents corrugations formed in the center of the bed-plate *z* and are designed to serve as cleats.

5 represents pedestals traveling on the bed- 100 plate *z* and held thereto by the bolts 6, pro- jecting through the narrow or neck opening 7 from the guideway 3 and through the base of the pedestals, being locked thereto by the 105 nuts 8. The pedestals 5 are hollow and have the bearings 9 extending through the sides thereof and the openings 10 at the front thereof. 11 is a turret mounted on the top of each of said pedestals, and 12 represents 110

bolts extending from the narrowed neck portion 13 of the slot 14 in the turret 11 through the upper face of the pedestal 5 into the recesses 15 and securely fastened by the nuts 16. The turrets 11 have the extending portions 17 and 18 and the track 19 extending continuously therealong through said turret and extending portions.

20 is a crown traveling on the track 19 and 10 having the bearings 21 formed at its inner ends.

22 is a rack formed longitudinally on the inside of the crown 20 and projecting into the grooved portion 23 of the turret 11.

15 24 is an upright shaft, supported in a suitable bearing in the turret 11 and having a gear-wheel 25 meshing with the rack 22.

26 is a miter-wheel at the lower end of the shaft 24.

20 27 is a shaft extending from end to end of the machine through the bearings 9 in the sides of the pedestals 5 and broken at 28 and coupled and having the miter-wheels 29 meshing with the miter-wheels 26, consequently communicating the motion of the shaft to the racks 22, thus operating the crowns 20 forwardly or backwardly.

30 30 represents hand-wheels fixedly secured to the outer ends of the shafts 31 and having 35 mounted thereon at the inner ends thereof the miter-wheels 32, coacting with the miter-wheels 33. The turning of either of the hand-wheels 30 will rotate the shaft 27, which will in turn operate the miter-wheels 29, coacting with the miter-wheels 26, thus 40 rotating the shafts 24 and through the gear connection with the racks 22 move the crowns 20 backward or forward. The coupling of the shaft 27 at 28 will enable the hand-wheels to be operated independently of each other, and consequently the portion 45 of the shaft to which each is connected.

34 represents rotating knives formed similarly to the knives 7 and secured to the shaft 45 35, which are journaled in the bearings 21. 36 represents convex pulleys, fixedly secured to said shafts 35 and connected by the belts 37 to the driving mechanism. It will be thus seen that there are the rotating knives 50 7, which must be approached with the material to be operated upon in order to make use of their cutting edges, and the knives 34, which must be advanced to the material to be operated upon in order to secure the use 55 of their cutting edges. Again, it will be noticed that the knives 34 may be fixed at any angle at which it is desired to make a cut in the said material by setting the turrets 11, while the knives at the rear of the machine 60 form the means of making the straight cuts across.

38 is the running-gear of the carriage, formed of the inverted-U-shaped blocks 39, inside of which are journaled the rollers 40, 65 which travel on the prepared tracks 41 on

the standards. 42 is a shaft journaled in the blocks 39 and extending from one end of the machine to the other and carried by said running-gear in its movements and projecting slightly beyond the said blocks at each 70 end of the machine having the keyway 43 in said projecting ends. 44 is a rod extending the full length of the machine and through the said blocks 39, having the nut-fastenings 45 at each end thereof. 46 represents 75 sections of tubes encircling the rod 44 between

the standards and forming a means of spacing the parts just above said standards and with the rod 44 generally bracing and tying the machine. 47 is a hand-wheel at the end 80 of the shaft 48, which is journaled in a bracket 49, secured to the bed-plate and the floor and also journaled at its inner end in the frame of the machine at 50. 51 is a miter-wheel mounted at the end of the shaft 85 48.

52 is a shaft extending the full length of the machine and journaled in the bearings 53, supported by the standards, and having mounted thereon the miter-wheel 54, meshing with the miter-wheel 51, and the 90 gear-wheels 56, meshing with the racks 57, forming part with the blocks 39, thus providing the means of moving the said running-gear of the carriage forwardly and rearwardly on the standards of the machine. 58 95 represents brackets having the supporting table portion 59 and the split lower extension 60 and the bearing 61, through which passes the shaft 42, the split portion 60 being securely clamped to said tubes 46. 62 100 is an angle-iron having a base-section 63 thereof bolted to the table portion 59 and an upwardly-extending section 64 and the section 65 extending over the table portion from said upward section 64 and formed to 105 spread over the material to be cut. 66 is a dovetail groove or guideway formed on the said brackets 58 adjacent to the table portion 59. 67 is a shoe having its tailpiece 68 correspondingly formed to the dovetail groove 66 and sliding therein. 69 is a rack forming part with said tailpiece. The shoe 67 is provided with recesses 70 from the inner surface of the upwardly-projecting portion 71, said recesses terminating in the orifices 72. The spiral springs 73 are introduced in said recesses. 110

74 is an angle-iron clamp formed to spread over the material to be cut and having an angular formation following the line of the cut 115 to be made and having the bolt-holes 75.

76 is a buffer introduced between the inner surface of the shoe 67 and the outer surface of the angle-iron clamp 74.

77 represents bolts extending through the 125 orifices 72, the spiral springs 73, and the correspondingly-threaded orifices 78 in the buffers 76 into the bolt-holes 75 in the angle-iron 74. The springs 73 continually press on the buffers 76, which in turn are pressing 130

on the clamps 74, thus forming a means of equalizing the pressure on the clamp and accommodating an uneven surface in the material.

5 79 is a removable table resting on the table portions 59 of the brackets 58 and extending for the full length of the machine. This table may be of any desired thickness, or if necessary an additional board may be added 10 thereontop, and in this connection it may be here pointed out that this simple means of adjustability in regard to thickness of the table is a very salient feature in the invention and not known, as far as I am aware, 15 in this class of machine, for it does away with all forms of complicated mechanism for raising and lowering that portion of the machine or the knives.

80 is the belt-rail, which is here shown as 20 the material to be operated upon.

81 represents segmental gears mounted on the shaft 42 immediately beneath the rack 69 and meshing with said rack and secured to said shaft with the set-screws 82.

25 83 represents levers secured on the projecting ends of the shaft 42 and keyed thereto at 43. It will be seen that on throwing the levers over one way or the other the tailpiece 68 is drawn backwardly or forwardly, as the case 30 may be, and consequently alter the position of the clamp 74 in relation to the belt-rail 80, which is resting on the table 79, thus forming a means of forcing the said belt-rail against the angle-iron 62 and therewith securely 35 clamping it on the table 79.

84 is a pawl engaging the ratchet-wheel 85, secured on the shaft 42. The pawl 84 has the weighted portion 86, which is sufficient to keep the point 87 of the said pawl from engagement with the ratchet-wheel 85. Thus 40 the clamping mechanism is freely turned inwardly or outwardly. The pawl when placed in engagement with the ratchet-wheel holds the clamp 74 in position. In order to provide a locking device, a small dog 88 is dropped over at the point 89 on the blocks 39. This dog 88 may be thrown over at any 45 time it is desired to lock the pawl in engagement with the ratchet-wheel and retain the pressure of the clamping mechanism on the 50 belt-rail.

Having described the various parts in detail, I shall now more particularly explain the operation thereof. The pulleys *j* and 36 55 are set in motion, rotating the knives *l* and 34. The belt-rail to be operated upon is then laid on the table 60, extending probably the full length of the machine. The knives *l* are adjusted on the shaft *h* to a position opposite 60 each of the places at which the cuts are to be made in the belt-rail. This is accomplished by merely loosening the set-screw fastening the said knives to the shaft and slipping said knives along. The knives 34, journaled in 65 the crown of the turrets on the pedestals 5,

are set at the proper angle at which the cut is to be made in the belt-rail by loosening the set-screws 12 and turning the turret on said pedestals until the blade of the knife points in the direction in which it is intended to make the cut in the rail. The set-screws 12 are then tightened up, firmly securing said turret in proper position. The pedestals are then pried along the bed-plate *z* by inserting the point of a lever under the base of the pedestals and against one of the corrugations or cleats 4. Each pedestal is thus moved to the position where it is desired to make the cut in the belt-rail. One or both if the shaft 27 is uncoupled of the hand-wheels 30 are then 70 turned, rotating the shafts 31, which in turn rotate the miter-wheels 29. This operates the miter-wheels 26 at the bottom of the shafts 24, thus turning the pinions 25, which engage the racks 17, forming part of the crowns 75 15. The crowns 20, moving inwardly over the table, bring the knives 34, which are continuously rotating, into contact with the belt-rail to make the necessary cuts therethrough. The shape of the knives is a very important feature 80 in this invention, as the upturned flange at each side of the knife insures a clean cut on each side of the slot made in the belt-rail. The splintering of the belt-rail is prevented by the angle-iron 74 extending angularly 85 alongside the part of the belt-rail in which the slot is to be made. When the knives have made the cut necessary in slotting the belt-rail, they are drawn back by again turning the hand-wheels 30, and the belt-rail is 90 100 then ready for the straight cuts to be made by the knives *l*. The hand-wheel 41 is then turned. This turns the miter-wheel 54, which rotates the shaft 52, and mounted on the said shaft are the gear-wheels 56, meshing 105 with the racks 57 on the blocks 39. The carriage is thus propelled toward the knives *l*, for as the said gear-wheels rotate the running-gear 40 of the carriage travels inwardly on the prepared tracks 57 and carries the belt-rail under the knives *l*, which make the necessary slots therein and complete the manufacture of said belt-rail. The circular saws 90 are provided at each end of the shaft *h* and saw off any extra length on the ends of the 110 belt-rail. The lever 83 is then thrown over, which releases the clamping mechanism, and the belt-rail is then removed without difficulty and is finished. Another belt-rail is 115 placed on the table, and the same operation 120 occurs.

The great advantage of this particular construction of the machine is that without removing the belt-rail from its first position the said belt-rail may be completely finished 125 on the one machine, and it is particularly in the manner of holding the said belt-rail and the arrangement of the parts so that it shall be in proper position that largely tend to make the operation of the machine successful. 130

What I claim as my invention is—

1. In a machine of the class described, in combination, a plurality of standards, a shaft journaled in the upper and the inner portion of said standards, a plurality of rotating knives mounted on said shaft, a carriage formed of a pair of inverted-U-shaped blocks having rollers mounted therein traveling on a prepared track on said standards, and a plurality of rods extending the full length of said machine and supported in said blocks, and brackets secured to said rods having a table portion, a suitable guideway in proximity thereto, clamps having a suitable tailpiece and a rack on said tailpiece and traveling in said guideways on said brackets, segmental gears meshing with said racks and mounted on a rotatable shaft therebeneath, levers fixedly secured to said shaft, angle-irons secured 20 to said brackets opposite said clamp, a bed-plate extending along the front of the machine, pedestals slidably arranged on said bed-plate, turrets mounted on said pedestals having extending portions forming guideways, crowns slidably arranged on said guideways, bearings supported by said crowns at the inner ends thereof, a shaft journaled in said bearings, rotating knives mounted on said shaft, means for moving the aforesaid 30 carriage, and means for adjusting said crowns, as and for the purpose specified.

2. In a machine of the class described, in combination, a plurality of standards, shafts journaled in said standards, rotating knives mounted on said shafts, a carriage traveling on said standards, and a clamping mechanism secured on the brackets forming the body of said carriage and formed of a fixed angle-iron secured to said brackets and a movable 40 angle-iron opposed thereto, a shoe supporting said movable angle-iron having a tailpiece traveling in a suitable guideway on said brackets, and means for controlling the movements of said tailpiece in said bracket, as and 45 for the purpose specified.

3. In a machine of the class described, in combination, a plurality of standards, shafts journaled therein, rotating knives mounted on said shafts, a carriage traveling on said standards, a clamping mechanism secured to the brackets forming the body of said carriage and formed of an angle-iron fixedly secured to the table portion of said brackets, a movable angle-iron opposed thereto, a shoe 50 supporting said movable angle-iron having a tailpiece traveling in a guideway in said bracket, said tailpiece having a rack forming part therewith, a gear meshing with said rack and mounted on one of said shafts, and a lever secured to said shafts and operating said gear, as and for the purpose specified.

4. In a machine of the class described, in combination, a plurality of standards, shafts journaled in said standards, rotating knives mounted on said shafts, a carriage supported

by a suitable running-gear mounted on said standards and having shafts extending the full length of said machine supported in said running-gear and brackets secured on said shafts, a table extending the full length of 70 said machine and supported on the table portions of said brackets, a clamping mechanism formed of an angle-iron fixedly secured to each of said brackets and abutting the side of said table, a movable angle-iron opposed to 75 said fixed angle-iron moving along the surface of said table, a shoe at the rear of said movable angle-iron, having a tailpiece traveling in the guideway on said brackets, a buffer 80 inserted through said shoe, and said buffer supporting said movable angle-iron, and means contacting with said tailpiece for controlling the movement of said angle-iron, as 85 and for the purpose specified.

5. In a machine of the class described, in combination, a plurality of standards, shafts journaled therein, rotating knives mounted on said shafts a carriage formed of a plurality of shafts extending the full length of the machine supported in a suitable running-gear traveling on said standards, a plurality of brackets secured to said shafts, a removable table supported on the table portions of said brackets, a clamping mechanism secured to 90 said brackets formed of a fixed angle-iron having an angularly-shaped section extending over the material to be operated upon, and its upright section abutting said table, a movable angle-iron opposing said fixed angle-iron and moving over the upper surface of said table, a shoe having a plurality of recesses in the face thereof and a tailpiece extending therefrom sliding in a dovetail groove formed on said bracket, said tailpiece having a rack 100 forming part therewith, a buffer between said shoe and said movable angle-iron, a plurality of bolts extending from the rear of said shoe into said recesses and through said buffers and into said movable angle-iron, a plurality 105 of coil-springs inserted in said recesses and exerting an equalizing pressure on the back of said buffer, segmental gears mounted on one of said carriage-shafts and meshing with the racks on said tailpieces, and a plurality 110 of levers fixedly secured to said carriage-shaft carrying said segmental gears and operating said clamping mechanism, as and for the purpose specified.

6. In a machine of the class described, in 120 combination, a plurality of standards, shafts journaled therein, rotating knives mounted on said shafts, a carriage formed of a suitable running-gear traveling in said standards, a plurality of shafts extending between and supported by said running-gear, and a plurality 125 of brackets secured to said shafts having suitable table portions and a dovetail groove forming a guideway, a clamping mechanism formed of an angle-iron fixedly 130

secured to said bracket and having its upper horizontal section thereof extending over the material to be operated, a movable angle-iron opposing said fixed angle-iron and supported by a shoe having a dovetail tailpiece, traveling in said dovetail groove and supporting and controlling said movable angle-iron, said dovetail tailpiece having a rack forming part therewith, a segmental gear mounted on one of said carriage-shafts and meshing with said rack, a lever fixedly secured to said carriage-shaft and operating said segmental gear, a ratchet-wheel secured to said carriage-shaft, a pivoted pawl on said

running-gear frame engaging said ratchet-wheel and having a weighted handle insuring its non-engagement with said ratchet-wheel, and a dog pivoted on said running-gear frame contacting with said handle and locking said pawl to its engagement with said ratchet-wheel, as and for the purpose specified.

Signed in the city and district of Montreal, in the Province of Quebec, in the Dominion of Canada, this 5th day of February, 1906.

ALEXANDER LECLAIR.
